DESIGN FOR A TEXTILE FABRIC OR THE LIKE

Louis Goldstein, Brooklyn, N. Y., assignor to Claremont Embroidery Co., Union City, N. J., a corporation of New Jersey

Application June 27, 1940, Serial No. 93,283

Term of patent 3½ years

To all whom it may concern:

Be it known that I, Louis Goldstein, a citizen of the United States, residing in Brooklyn, county of Kings, State of New York, have invented a new,
original, and ornamental Design for a Textile Fabric or the like, of which the following is a specification, reference being had to the accompanying drawing, forming part thereof.

The figure of the drawing is a plan view of a textile fabric showing my design, the unit of which being indicated by dot-dash lines.

I claim:

The ornamental design for a textile fabric or the like, as shown and described.

LOUIS GOLDSTEIN.
